UNITED STATES PATENT OFFICE

HOWARD T. HALLOWELL, OF JENKINTOWN, PENNSYLVANIA, ASSIGNOR TO STANDARD
PRESSED STEEL CO., OF JENKINTOWN, PENNSYLVANIA, A CORPORATION OF PENN-
SYLVANIA

SIGN FRAME CLAMP

Application filed December 22, 1930. Serial No. 503,901.

My invention relates to means for supporting or suspending various types of signs, including hanging or suspended signs and signs of the type supported or mounted upon pedestals or standards.

These signs usually include an enclosing rim or frame for clamping or otherwise embracing a plate or disk constituting the sign proper, and one object of my invention is to provide improved means for connecting these rims or frames.

A further object of my invention is to provide an improved type of adjustable clamp for such rims or frames; which clamp may be associated with supporting or suspending means of various kinds.

These and other features of my invention are more fully described hereinafter; reference being had to the accompanying drawings, in which:

Figure 1 is a view in elevation of one form of hanging sign structure made up of a rim or frame and connecting and supporting means therefor, within the scope of my invention.

Fig. 2 is an enlarged outside view of one of the clamping brackets associated with the supporting means.

Fig. 3 is an inside view of one of the bracket members.

Fig. 4 is an end elevation of the same.

Fig. 5 is a sectional view on the line *a*—*a*, Fig. 2.

Fig. 1^a is a view in elevation of another sign structure of the hanging type, having a rectangular frame or rim, within the scope of my invention; such view showing a modified form of clamping and supporting means.

Fig. 2^a is an outside view of one of the bracket supports shown in Fig. 1^a, on an enlarged scale.

Fig. 3^a is an inside view of the bracket support shown in Fig. 2^a.

Fig. 4^a is an end elevation of the same.

Fig. 5^a is a sectional view on the line *b*—*b*, Fig. 2^a.

Fig. 1^b is a view in elevation of another form of sign, in this instance circular in form, supported upon a pedestal and held

thereto by a bracket clamp within the scope of my invention.

Fig. 2^b is an enlarged outside view of the supporting bracket shown in Fig. 1^b.

Fig. 3^b is an inside view of the supporting bracket shown in Fig. 2^b.

Fig. 4^b is an end elevation of the same.

Fig. 5^b is a sectional elevation on the line *c*—*c*, Fig. 2^b.

Fig. 1^c is a view in elevation of another form of bracket support for a sign supported by a pedestal; such sign being substantially of the same type as that shown in Fig. 1^b.

Fig. 2^c is an enlarged outside view of the supporting bracket shown in Fig. 1^c.

Fig. 3^c is an inside view of one of the members of the supporting bracket shown in Fig. 2^c.

Fig. 4^c is an end elevation of the supporting bracket shown in Fig. 2^c.

Fig. 5^c is a sectional view on the line *d*—*d*, Fig. 2^c, and

Fig. 6 is a cross sectional view of one form of rim or enclosing frame for the several signs; such view being taken on the lines VI—VI, of Figs. 1, 1^a, 1^b and 1^c.

The sign proper may be made of or comprise a central plate 1 of any suitable character, single or duplex as the case may be, and such plate (or plates) may carry indicia of any character and may include lighting fixtures. The sign plate forms no part of my invention.

In carrying out my invention, the sign plate 1 is enclosed by a rim or frame 2 which may be of the cross sectional shape or contour illustrated in Fig. 6, comprising a web with annular ribs 2^a and 2^b. The ribs 2^a may be in the form of marginal flanges with which the clamping bracket elements of the supporting means will engage, while the ribs 2^b are substantially centrally disposed and provide between them an annular groove 2^c for the reception of the marginal edge of the sign plate 1.

The rim or frame is clamped about the sign plate 1, and for this purpose it is a discontinuous element; the terminals being in separated condition and provided with upstanding ears 3, as illustrated in Figs. 2, 3, 100

2^a, 3^a, et seq. While these ears may be formed by bending the ends of the rim or frame 2, they are preferably separate pieces, welded as at 3^a to the adjacent ends of said rim and subsequently secured together whereby such rim or frame may exert a clamping effect upon the sign plate, by means of a bolt 4. This type of rim or frame is particularly advantageous for use in supporting a sign plate, inasmuch as it tightly grips the sign and is very rigid laterally.

The bracket clamping members preferably comprise matching sections 5 of similar contour and construction, which are arranged in pairs and disposed on opposite sides of the rim or frame 2 at suitable points, with marginal or other bosses or flanges 6 on their inner faces, which bosses or flanges lie substantially in engagement with each other when said bracket clamping members are placed in clamping position relatively to the rim or frame 2 which encloses the sign plate 1. These bracket members may be held in clamping position by bolts 7. The marginal bosses or flanges 6 on the inner faces of these bracket members are notched at 8 in order that the flanges of the rim or frame 2 may be properly engaged and supported thereby. One of the clamping bracket supports will always conceal the connection for the rim or frame, and the other may be placed in complementary relation thereto. The clamping brackets may be suspended by straps 9 from yoke members 10 carried by a rod or other similar support 11; such straps having substantially hook-shaped ends 9^a, and the bracket clamping members are provided with matching bosses 12 which are engaged by the hooked ends of said straps.

The structure illustrated in Figs. 1^a, 2^a, et seq., is substantially like that illustrated in Figs. 1, 2, et seq., excepting that the sign structure is provided with a rectangular frame or rim, and such frame or rim may be supported at the upper corners. In this instance the rim or frame may comprise two pieces, indicated at 2 and 22, which may be connected together at the points of attachment of the bracket clamping supports 5, and in lieu of welding ears to these portions of the frame or rim, as in the form of structure illustrated in Figs. 1, 2, et seq., I may turn the ends of these pieces in the manner illustrated at 22^a in Fig. 2^a, and hold the same together by the usual bolt 4. It will be understood, of course, that I may weld ears to the members 2 and 22, shown in Figs. 1^a, 2^a, et seq., instead of bending the ends of such portions.

In other respects, the character of the bracket supporting clamps shown in Figs. 1^a, 2^a, et seq., is substantially the same as that illustrated in Figs. 1, 2, et seq., except as it may be modified for the engagement with the rim or frame members engaging the sign

plate and disposed substantially at right angles to each other. In this instance the sections of the bracket clamping members 5 have their flanges or bosses 6 notched at 8 in lines substantially at right angles to each other. In addition, this form of the bracket clamp may have its sections notched at 8^a to form openings when such parts are clamped together permitting access to the bolts connecting the sections of the rim or frame should it be desired to tighten the engagement of the same with the sign plate. This form of bracket clamping member will be supported or suspended in the manner illustrated with respect to the structure shown in Fig. 1.

In Figs. 1^b, 2^b, et seq., I have shown a form of clamping bracket support which may be carried by a standard or pedestal mounting in the form of a post 15. In this arrangement, the bracket clamping support comprises matching sections 5^b held together and in contact with the flanges of the rim or frame 2 by the bolts 7^b. Instead of having internal bosses to be engaged by a depending strap, as in the form of structures illustrated in Figs. 1, and 1^a, it may have semi-circular portions 16 forming a sleeve adapted to receive the upper end of the post 15, which may be tubular or of other construction and to which the bracket clamping members 5^b may be secured, as by a suitable bolt as indicated at 17. These clamping bracket supports are preferably provided internally with projections 18, against the under side of which the upper end of the post abuts, as clearly indicated in Fig. 3^b.

In all of the structures hereinbefore described, the bracket clamping members are of matching construction so that no "rights" or "lefts" are needed in assembling those of the same type or character. They are all arranged for clamping engagement with the rim or frame supporting the sign plate; being held together and in clamping position by suitable bolts, and they are also arranged to cover the connection or connections between the section or sections making up the enclosing frame or rim for such sign plate.

In the structure illustrated in Figs. 1^c, 2^c, et seq., I have shown another form of clamping bracket support particularly designed for use in connection with pedestal or standard supports of the post type, such as illustrated in Figs. 1^b, 2^b, et seq.

In this instance, showing a circular sign plate, such plate will be carried by a circular frame or rim 2 of the same character as those illustrated in the other figures of the drawings and the ears 3, which may be welded to the termini of said rim or frame, may be connected together by a bolt 4 in the usual manner.

The supporting and clamping element whereby the rim or frame of the sign plate

shown in Fig. 1^c is secured to the post or pedestal 15, may comprise sections 20 and 21; the section 20 being illustrated as having a threaded sleeve portion 20^a forming a socket whereby it may be mounted on the upper threaded end of said post. It will be understood, of course, that any suitable socket connection into which the upper end of the post may be inserted and to which it may be secured by a bolt or other fastening device, is within the scope of my invention. And, if desired, the section 20 may be provided with an externally threaded end adapted to enter the upper end of the post, which may be internally provided with threads for cooperative engagement therewith. The section 21 is a matching section, omitting the socket portion 20^a, however, and it will overlie the section 20 in the manner illustrated in Figs. 2^c and 4^c; such section 21 being secured to the section 20 by means of bolts 7^c which serve to clamp such sections in proper engagement with the flanges of the rim or frame 2. These sections have overlying flanges for the rim or frame as indicated at 6^c of a character substantially identical with the flanges of the clamping bracket members shown in Figs. 2^b and 4^b, and their function is the same.

30 It will be understood that I have provided a simple and efficient structure for the purpose described; one that may be assembled and detached with great facility so as to permit alterations or changes in the sign plates carried thereby. At the same time, the bracket clamping members are of substantial character and form a substantially permanent connection and support.

I claim:

40 1. The combination with a sign-plate-enclosing rim or frame, of a pair of matching clamp members each comprising a plate or web having flanges on one side or face in matching relation; certain of said flanges being recessed to provide seats for the edges of the rim and having portions overlying the latter, and means for holding said matching members in clamping engagement with said rim thereby forming a box-like structure over said rim.

50 2. The combination with a sign-plate-enclosing rim or frame and clamping means therefor, of a pair of matching clamp members each comprising a plate or web covering the means clamping said rim and having flanges on one side or face in matching relation; certain of said flanges being recessed to provide seats for the edges of the rim and having portions overlying the latter, and means for holding said matching members in clamping engagement with said rim thereby forming a box-like structure over said rim.

60 3. The combination with a sign-plate-enclosing rim or frame, of a pair of matching clamp members each comprising a plate or

web having flanges on one side or face in matching relation; certain of said flanges being recessed to provide seats for the edges of the rim, means for holding said members in clamping engagement with said rim and the 70 edges of the flanges on each of the plates in matching relation thereby forming a box-like structure over said rim, and matching bosses carried by the walls of said clamping members in aligned position for engagement with 75 supporting means.

4. The combination with a sign-plate-enclosing rim or frame and clamping means therefor, of a pair of matching clamp members each comprising a plate or web covering the rim-clamping means and having flanges on one side or face in matching relation; certain of said flanges being recessed to provide seats for the edges of the rim, matching bosses internally disposed on the 80 walls of said clamp members in aligned position for engagement with supporting means, and bolts for holding said members in clamping engagement with said rim thereby holding said clamp members in a box-like assem- 85 bled position over said rim and supporting means. 90

5. The combination, in a sign structure, of a sign plate, a flanged rim following the perimeter of the same and having a groove receiving the edge of the sign plate, means for clamping said rim to the sign plate, supporting means for said flanged rim comprising a pair of matching clamp members each consisting of a plate or web having flanges on 95 one side or face in matching relation; said flanges being turned inwardly with respect to said sign plate, and certain of said flanges being recessed to provide seats for the edges of the sign-plate-engaging rim, means for holding said clamp members in clamping engagement with the rim over the meeting ends of the same and thereby forming a box thereover, and means for supporting said rim-engaging clamp members. 100

6. The combination with a sign plate, of a sign-enclosing frame, clamping means carried thereby for drawing the frame around the sign plate and tightly gripping the same, and an additional clamping member comprising a pair of web or plate portions with frame-fitting jaws to grip said frame in its sign-clamping position; said frame-fitting clamping jaws forming a box covering the frame clamping means. 110

7. The combination with a sign plate, of a sign-enclosing frame, clamping means carried thereby for drawing the frame around the sign plate and tightly gripping the same, and an additional clamping member comprising a pair of web or plate portions with frame-fitting jaws to grip said frame in its sign-clamping position; said frame-fitting clamping jaws forming a box about the frame clamping means. 120

8. The combination with a sign plate, of a plate enclosing rim, means forcing said rim into intimate contact with said sign plate, a support for said sign, and means, shaped as a closed box embracing said last named means for concealing said means, assisting the maintenance of the contact of said rim with said sign plate, and connecting said sign to a support.
- 10 9. The combination of a pedestal forming a supporting member, a sign plate, a rim or frame having flanges providing a groove receiving said sign plate and secured thereto, clamping means for securing the rim carrying said sign plate to said pedestal comprising detachable matching plates with flanged portions overlying the edges of said rim, and bolts for securing said matching plates together and in clamping engagement with said rim and said flanges in matching relation to form a box-like structure over said rim; one of said rim clamping members having socketed engagement with said post or pedestal.
- 15 20 25 In witness whereof I have signed this specification.

HOWARD T. HALLOWELL.
